UNITED STATES PATENT OFFICE

155,256

DESIGN FOR AN AIRPLANE

Alex Francis Arcier, Dayton, Ohio, assignor to
The Waco Aircraft Company, a corporation of
Ohio

Application September 17, 1947, Serial No. 141,446

Term of patent 7 years

(Cl. D71—1)

To all whom it may concern:

Be it known that I, Alex Francis Arcier, a citizen of the United States of America, residing in the city of Dayton, in the county of Montgomery and State of Ohio, have invented a new, original, and ornamental Design for an Airplane, of which the following is a specification, reference being had to the accompanying drawing, forming a part thereof.

Fig. 1 of the drawing is a plan view of an airplane embodying the new design;

Fig. 2 is a front elevational view of the same;

Fig. 3 is a side elevational view thereof; and

Fig. 4 is a rear perspective view of the same airplane.

I claim:

The ornamental design for an airplane, substantially as shown.

ALEX FRANCIS ARCIER.
